UNITED STATES PATENT OFFICE.

CHARLES W. JACKMAN AND MILES M. JACKMAN, OF WATERLOO, INDIANA.

ROTARY PUMP.

1,268,248.

Specification of Letters Patent. Patented June 4, 1918.

Application filed June 12, 1916. Serial No. 103,200.

To all whom it may concern:

Be it known that we, CHARLES W. JACKMAN and MILES M. JACKMAN, citizens of the United States, residing at Waterloo, in the county of Dekalb and State of Indiana, have invented certain new and useful Improvements in Rotary Pumps, of which the following is a specification.

The present invention relates to pumps and more particularly to rotary pumps of the radial flow type.

An object of our invention is to provide a rotary pump in which water or other propelled fluid is received at the axis of the rotor and flows radially to be propelled in a given direction.

Another object of our invention is to provide a rotary pump which is reversible without the necessity of throwing clutches or altering any of the relations of the mechanical parts of the device.

A further object of our invention is to provide a rotary pump of the class above described employing rotary abutments for coaction with the pistons of the rotor, suitable gearing being provided which remains unchanged through the operation of the pump in either direction.

Other objects and advantages to be derived from the use of our invention will appear from the following detail description and the claims, taken with an inspection of the accompanying drawings in which:

Figure 1 is a side elevation of a pump embodying the improvements of our invention;

Fig. 2 is a vertical transverse sectional view taken on the line 2—2 of Fig. 1, looking in direction of the arrow;

Fig. 3 is a longitudinal vertical sectional view taken on the longitudinal axis of the pump stator;

Fig. 4 is a longitudinal sectional view taken on the line 4—4 of Fig. 3 looking in direction of the arrow.

Referring more particularly to the drawings, wherein similar characters of reference designate like and corresponding parts throughout the various views, 1 designates in its entirety the casing or stator having a base portion 2 and a rotor receiving or

water chamber 3. The stator is provided with a pair of semi-cylindrical enlargements 4 and 5 on its peripheral wall 6 for a purpose which will hereinafter appear. The stator 1 is preferably formed in two detachable sections, lugs 4' and 5' being formed on the enlargements 4 and 5 for the purpose of detachably connecting the two sections of the stator. Suitable packing material may be provided (not shown) to prevent the escape of the propelled fluid.

The rotor of our invention embodies preferably a drum like body 7 provided with a central diametrically extending tube or the like 8 divided by a longitudinally extending partition 9 twisted at the points 10 and 11 adjacent its extremities to form pistons 12 and 13. The partition 9 forms a pair of conveying ducts 14 and 15 opening, respectively, in the direction of rotation in front of and behind the pistons 12 and 13, as best shown in Fig. 3. In the present instance the duct 14 forms the inlet duct, fluid entering through an axially located opening 16 communicating with a fluid supply pipe 17 through an opening 18 formed in an enlargement 19 cast integrally with the stator body, as best shown in Fig. 2. The outlet duct 15 communicates with an axially arranged opening 20 in the opposite side wall 21 of the rotor 7, said opening 20 communicating with an exhaust or outlet pipe 22 by means of an opening 23 formed in an enlargement 24 arranged similarly to the enlargement 19. In order to form bearings for the rotor 7 lateral annular extensions 25 are formed on the side walls of said rotor for reception in complementally formed recesses. As best shown in Fig. 2 the side wall 21 of the rotor 7 is thickened and provided on the peripheral surface thereof with a plurality of teeth 26 for a purpose which will herein-after appear.

We provide abutments for co-operation with the pistons 12 and 13, these abutments being preferably of the rotary type and embodying substantially semi-cylindrical members 27 and 28, the peripheral walls of said members being provided with inwardly extending cylindrical portions 29 and 30 forming

ing recesses 31 and 32 adapted to alternately receive and accommodate the pistons 12 and 13 as the same revolve. The end portions of the abutments 27 and 28 are provided with 5 stub shafts 33 journaled in suitable openings in the side walls of the stator 1. The abutments 27 and 28 are adapted to be rotated simultaneously with the rotor 7 and so relatively thereto that as the pistons 12 and 13 10 pass said abutments the recesses 31 and 32 will be presented to receive said pistons and move therewith to allow passage of the latter therefrom. In order to accomplish this the abutments 27 and 28 are provided with 15 gear teeth 34 which are adapted to mesh with the gear teeth 26 formed on the rotor. In order to prevent the escape of fluid when the pistons are in the neutral position as best shown in Figs. 3 and 4 we provide tongues 20 or extensions 35 on the rotor 7 above and below the pistons 13 and extending radially from said rotor, said extensions 35 being arranged to engage the edges of the abutments 27 and 28 to close any opening which might 25 be formed at this point in operation.

Power is given to the rotor by means of a shaft 38 integrally formed therewith and having a pulley 39 on one end. If desired the shaft 38 may terminate at the partition 30 9 instead of passing across the entire width of the stator casing. However, as shown the shaft tends to stabilize the rotor during 35 operation.

In operating water or some such propelled fluid is admitted through the pipe 17 and the opening 16 into the inlet duct 14. Assuming the pump is in the position as in Fig. 3 the fluid now passes out through both ends of the duct 14 and against the 40 pistons 12 and 13 and the abutments. The motor is revolved in a clockwise direction. After a half revolution has been completed the pump chamber will be full of fluid admitted behind the pistons 12 and 13 which 45 during the next half revolution will be conveyed through the duct 15 which opens in front of the pistons 12 and 13 and thence outwardly through the exhaust pipe 22, while at the same time fluid will be admitted 50 behind the pistons as before. The continual meshing of the gear teeth 26 and 34 will rotate the abutments in order to bring the recessed portions thereof into position to receive the pistons at each half 55 revolution. It will be clear that the direction of rotation of the rotor may be reversed by merely reversing the direction of the driving pulley, that is, by employing the outlet pipe 22 as the inlet pipe, and the pipe 60 17 as the outlet pipe. The simplicity of structure of our invention obviates the necessity of providing complicated controlling levers and the like for shifting the abutments, and it will be noted that the rotor,

inlet and outlet ducts, shaft, and pistons are 65 all cast integrally forming a compact and durable structure. It will be noted that the parts of the invention may be readily assembled, the two halves of the stator casing being separated and the motor placed in 70 operative position. By returning the upper half of the stator casing to the position shown in the drawings and placing the fastening bolts in position the device is ready for use. We desire to lay particular stress 75 upon the fact that the device of our invention, owing to its simplicity of construction, may be readily adapted for use as a fluid motor, without structural alteration.

From the above description taken in connection with the accompanying drawings, it is thought that a clear and comprehensive understanding of the construction, operation and advantages of our invention may be had, and while we have shown and described our invention as embodying a specific structure, we desire that it be understood that we may make such changes on said structure as do not depart from the spirit and scope of the invention as claimed. 80

What we claim as new and desire to secure by Letters-Patent is:—

1. The combination of a rotary pump having a rotor provided with pistons and oppositely extending radial ducts spirally twisted 85 to present oppositely directed openings on each side of said pistons, a plurality of rotatable abutments having recesses adapted to be positioned at times to receive the pistons for the purpose set forth. 100

2. The combination with a stator casing having a plurality of rotatable abutments therein, of a rotor intergeared with said abutments and comprising a drum like body having a tube extending diametrically therethrough, a partition in said tube being twisted adjacent its free extremities to provide radially extending pistons, said partition forming inlet and outlet ducts oppositely arranged alternately, and inlet and outlet pipes communicating with said inlet and outlet ducts. 105

3. In a rotary pump the combination with a stator casing formed in two detachable sections provided with complementally arranged enlargements, rotatable abutments receivable in said enlargements, said abutments having recesses, of a rotor mounted in said casing of drum like form having a diametrically extending tube, a partition in said tube twisted adjacent its free extremities to form pistons for engagement in the recesses in said abutments, said rotor receiving fluid axially thereof and discharging the same peripherally thereof during 115 rotary motion and gear teeth on said rotor and said abutments whereby to transmit movement from said rotor to said abutments 120

in order to cause the latter to co-act with said pistons when said rotor is operating.

4. In a rotary pump the combination of a stator, a rotor operable therein having a 5 radially extending tube therethrough, a partition, extending through said tube and twisted adjacent its ends, the extremities of said partition forming projecting pistons,

said partition forming outlet and inlet ducts on opposite sides of the pistons, and revolving abutments in the stator coöperating with said pistons. 10

In testimony whereof we affix our signatures.

CHARLES W. JACKMAN.
MILES M. JACKMAN.
